UNITED STATES PATENT OFFICE.

ERNEST E. BOYCE, OF GRAND RAPIDS, MICHIGAN.

DESIGN FOR A REFRIGERATING SHOW-CASE.

46,940.

Specification for Design.

Patented Feb. 16, 1915.

Application filed June 29, 1914. Serial No. 848,094. Term of patent 7 years.

To all whom it may concern:

Be it known that I, ERNEST E. BOYCE, a citizen of the United States, residing at Grand Rapids, in the county of Kent and State of Michigan, have invented a certain new, original, and ornamental Design for a Refrigerating Show-Case, of which the following is a specification, which, taken in connection with the accompanying drawing, fully discloses the design, such that others may understand the same.

The figure is a perspective view showing my design of show case.

This design for a refrigerating show case is shown as supported by a counter 1.

In its essential features the design is a show case having an inclined front and at each end of the case, a mirror 2 forms a part of said front of the case. The top of the

case above such mirror sections is formed of a slab 3. Between the end portions of the case the front is of transparent glass, through which appears the rack 4 and the doors 5 at the back of the case and through which may be seen any articles supported on the rack in front of the doors. The top of the case between the slabs 3 is of ordinary glass construction.

I claim:

The ornamental design for a refrigerating show case, substantially as shown and described.

In testimony whereof I affix my signature in presence of two witnesses.

ERNEST E. BOYCE.

Witnesses:

HOWARD H. YARRINGTON,
FRANK E. LIVERANCE, Jr.
